UNITED STATES PATENT OFFICE

2,440,108

OVERCURRENT PROTECTIVE SYSTEM FOR
A DIRECT-CURRENT LOAD CIRCUIT

Donald E. Maxwell, Scotia, N. Y., assignor to General Electric Company, a corporation of New York

Application May 5, 1943, Serial No. 485,745

3 Claims. (Cl. 175—294)

1

The present invention relates to a relay circuit for producing a time delayed operation under sudden fluctuations. One use of such a relay circuit is in connection with an overload relay for a load circuit having a high inrush current of short duration. Without the time delayed operation, the overload relay might be operated by the inrush current under conditions when there was no overload over a period of time sufficient to cause injury to apparatus in the load circuit.

The object of my invention is to provide an improved relay circuit for obtaining time delayed operation of a relay.

The novel features which I believe to be characteristic of my invention are set forth with particularity in the appended claims. My invention, itself, however, both as to its organization and method of operation, together with further objects and advantages thereof, may best be understood by reference to the following description taken in connection with the accompanying drawing in which the single figure is a diagram of my relay circuit applied to an overload relay for a rectifier.

Referring to the drawing, there is shown a rectifier 1 having output terminals 2 connected to a load represented by a resistance 3 and a condenser 4. The rectifier is fed through a transformer 5 having input terminals 6 connected to an A.-C. power supply through a normally open switch or circuit breaker 7. The switch has an operating coil 8 in series with a battery 9 through normally open contacts 10 controlled by a "start" button 11 and normally closed contacts 12 of an overload relay 13. By momentarily pushing the "start" button 11, the coil 8 is energized to close the switch 7 and to close contacts 12 completing a holding circuit for the coil 8 through contacts 15 normally closed by a "stop" button 16. Once the holding circuit is completed, the "start" button may be released and the switch 7 remains closed until either the contacts 15 are opened by the "stop" button or the contacts 12 are opened by operation of the overload relay 13.

Upon closing the switch 7, rectified current flows to the load. If the condenser 4 is large, the inrush current (limited primarily by the resistance between the output terminals 2 and the condenser 4), though of short duration, will be much larger than the normal load current. A quick acting current overload relay connected directly in the load circuit would be operated by the inrush current, causing the switch 7 to open. By holding the start button closed, the switch 7 would be reclosed as soon as the contacts 12

reclosed, and after one or more cycles the inrush current would be reduced by the charging of the condenser 4. The repeated operation (chattering) of the overload relay imposes an unnecessary load on the relay contacts.

In the present circuit, a time delay in the operation of the overload relay 13 is obtained by connecting the overload relay coil 17 in parallel with a condenser 18, the condenser being connected in series with a resistance 19 across a variable resistance 20 in the load circuit. From the resistance 20, a voltage corresponding to the load current is impressed on the time delay network consisting of the resistance 19, condenser 18, and the resistance and inductance of coil 17. The resistance and inductance of coil 17 should be relatively high, i. e., coil 17 has many turns of small diameter wire. This renders the relay of the sensitive D.-C. type, having a very low value of pick-up current. The circuit values are chosen so that the network is non-oscillatory and has a time delay in the build-up of current through the coil 17 sufficient to prevent operation of the overload relay by inrush currents which do not last long enough to endanger the rectifier. Under a gradually increasing load current, the charge on the condenser 18 and the current through the relay coil 17 follow the load current and the overload relay operates to open the contact 12 (and cause opening of the switch 7) as soon as the overload current reaches the value corresponding to the design of the relay and the setting of the variable resistance 20 (the smaller the resistance 20 the larger the overload current required to operate the relay). Under a suddenly increasing load current, such as the initial inrush current or the momentary overload caused by sparking of a tube in the load circuit, the current through the overload relay coil 17 cannot instantaneously follow the load current and does not reach a value sufficient to cause operation of the relay unless the overload current persists at least as long as the delay time determined by the constants of the relay circuit. The relay has "inverse time" characteristics, i. e., the greater the overload current the faster the relay operates to open contacts 12. The same time delay is present between opening and reclosing of the contacts 12. After opening of the contacts 12, the contacts 12 are held open for a short time by the discharge of the condenser 18 through the relay coil 17. If the start button 10 is held closed and the load is short-circuited, the overload relay will successively open and close the contacts 12, causing the opening and closing of the switch 7.

The length of time the switch 1 is closed will be such that the average current will be insufficient to cause damage.

This relay circuit permits the use of quick acting overload relays which are lighter and cheaper than "time delay" relays. The time delay and the overload setting are readily adjusted respectively by changing the circuit constants and by adjusting the resistance 20.

What I claim as new and desire to secure by Letters Patent of the United States is:

1. A rectifier control circuit, comprising a rectifier having input and output circuits, a circuit breaker in said input circuit, an operating coil for the circuit breaker in series with normally closed contacts of an overload relay, a start switch for selectively closing the operating coil circuit, a coil for the overload relay, a condenser in shunt with the relay coil and both the coil and condenser being in series with the rectifier output circuit through a resistance, said relay coil, condenser, and resistance being proportioned to comprise a non-oscillatory circuit and so as to obtain a time delay in energizing the relay coil by sudden fluctuations in the rectifier output.

2. In combination, an input circuit, a direct current load circuit coupled to said input circuit, a capacitor connected in series circuit relation with a resistor across a portion of said load circuit, a relatively quick-acting overload relay having an energizing winding connected directly in parallel circuit relation with said capacitor and in series with said resistor across said portion of said load circuit, said capacitor, resistor and winding forming a non-oscillatory timing circuit providing a predetermined delayed response to

sudden overload current variations in said load circuit, and means controlled by said relay for disabling said input circuit.

3. In combination, an alternating current input circuit, a direct current load circuit coupled to said input circuit and including a rectifier and a capacitive load element in series circuit relation, a relatively quick-acting overload relay operable to disable said input circuit and including a current responsive winding connected in series with a resistor across a portion of said load circuit, and a capacitor connected in parallel circuit relation with said current responsive winding and in series with said resistor across said portion of said load circuit, said winding, resistor and capacitor forming a non-oscillatory timing circuit effective to delay the response of said relay to sudden overload variations in current in said load circuit and also to delay the release of said relay after removal of said overload variations.
